SIPHON CLEANER

Clarence Reynolds, Louisville, Ky.

Application September 21, 1943, Serial No. 503,244

3 Claims. (Cl. 15—104.14)

This invention relates to a device for cleaning siphons such as are installed in locomotive fire boxes.

The use of thermal siphons in locomotive fire boxes for the purpose of increasing the circulation of water and improving the thermal efficiency is now quite common. As usually constructed, a siphon comprises a flat box depending vertically from the crown sheet into the fire box, having a tube formed at the bottom thereof extending downwardly to the lower portion of the boiler, the rounded bottom or tube opening into the upper portion of the siphon on its upper side. Clean-out openings are provided for inserting cleaning devices into the tubular or trough-like bottom of the siphons but the devices used for this purpose heretofore have not been capable of performing the cleaning operation satisfactorily. While various forms of tube cleaners have been proposed heretofore, none of them, so far as I am aware, is capable of satisfactorily cleaning the tubular bottom trough of a siphon. This results principally from the fact that the tube or trough of the siphon is open at the top for the greater portion of its length so that, when it is attempted to use ordinary tube cleaners having cleaning elements which are independently movable radially, the element which is opposite the open side of the siphon trough moves outwardly and on further rotation fouls against one side of the siphon.

I have invented a novel siphon cleaner by which I am enabled to clean the tubular bottom or trough of a siphon thoroughly and expeditiously. In a preferred embodiment, my invention comprises a central stud or stem having a plurality of pairs of arms and links pivoted thereon to each other, at least four in number. One arm of each pair has a cleaning element at the extreme end thereof in the form of a cutting wheel. The several pairs of arms and links are all tied together so that they move outwardly or inwardly simultaneously. One arm of each pair preferably comprises a flat bar while the link is of yoke shape. The yoke-shaped link is pivoted to the arm intermediate the ends of the latter and its sides are spaced sufficiently to admit the cutting wheel on the end of the flat bar arm when the arms and links are collapsed toward the central stud or stem. The flat bar arms are preferably pivoted to a block secured to the stud while the yoke-shaped links are pivoted to a block slidable thereon.

A complete understanding of the invention, its novel features and advantages, may be had from the following detailed description which refers

to the accompanying drawings illustrating the aforesaid preferred embodiment.

In the drawings:

Figure 1 is a side elevation showing the links in expanded position;

Figure 2 is a similar view showing the links in collapsed position;

Figures 3 and 4 are transverse sectional views taken along the plane of lines III—III and IV—IV respectively of Figure 2; and

Figure 5 is an elevation of the central stud.

Referring now in detail to the drawings, the siphon cleaner of my invention comprises a central stud or stem 10 having a socket 11 at one end thereof adapted to receive driving means such as the end of a flexible shaft remote from the driving motor. The stud 10 is threaded adjacent to socket 11 as at 12 and is thus adapted to receive an internally threaded boss 13 projecting from a block 14. The block is thus fixed to the stud. The block has a plurality of longitudinal slots 15 extending thereinto from the end remote from the boss 13. These slots intersect the central bore through the block which accommodates the stud. The number of slots should be greater than three. In the illustrated embodiment, I have shown four but any number greater than three may be used.

Arms 16 extending forwardly from the block 14 each have one end fitting into the slots 15 and pivoted therein on a pin 17. The arms 16 may conveniently be formed from flat bar stock. At the end thereof remote from the pin 17, each arm has a rounded, angularly disposed portion provided with a pin 18 seated in a suitable hole drilled therein and secured in place by an anchor pin 19. A cutting wheel 20 is journaled on the pin 18 on each of the arms to rotate about an axis which extends in the same general direction as the axis of rotation of the device (but not necessarily exactly parallel therewith) so that the cutting wheel has rolling contact with the inner curved surface of a siphon when the device is rotated therein.

Yoke-shaped arms 21 having a general appearance similar to that of a wishbone are pivoted to the links 16 intermediate the ends of the latter by pins 22. As clearly shown in the drawings, the links 21 have spaced sides or legs 23 and 24 extending the greater portion of their length which embrace the arms 16 and admit the cutting wheels 20 journaled thereon when the arms and links are collapsed towards the stud 10 as shown in Figure 2. The links 21 also have a portion 25 projecting from the end thereof re-

move from that traversed by the pin 22 and are bowed outwardly adjacent such portion. The portions 25 of the links 21 enter slots 26 formed in a block 27 slideable on the distal end of stud 10 and having a hub 28 fitting the latter closely. The links 21 extend rearwardly from and are pivoted to the block 27 by screws 29 threaded thereinto. The number of the slots 26, of course, corresponds to the number of slots 15 so that each of the arms 16 will have a mating link 21. Each pair of arms and links 16 and 21 constitutes an arrangement similar to a toggle. As shown in Figure 2 of the drawings, the links 21 are sufficiently bowed outwardly from the stud 10 adjacent the ends of the links which are connected to the sliding block 28 so that the outer surfaces of such bowed portions are farther from the stud than the cutting wheels when the device is collapsed. The nesting of the cutting wheels 20 within the bifurcated links 21 reduces the diameter of the device to a minimum when the device is collapsed and also serves to protect the cutting wheels from injury or from marring surfaces against which the device may come in contact when collapsed. Such protection is made particularly effective when the links 21 are bowed outwardly, as shown in Figure 2, so that they extend outwardly beyond the nested cutting wheels when the device is collapsed. The cutting wheels are journaled on axes which are sufficiently inclined inwardly from the axes of their supporting arms so that the axes of the cutting wheels are substantially parallel with the inner surface of the siphon when the device is expanded, as shown in Figure 1. The mounting of the cutting wheels on their supporting arms, furthermore, is such that the outer surfaces of the arms are farther from the axis of the stud than the cutting wheels when the device is collapsed, thus further protecting the cutting wheels when the device is collapsed.

It will be evident that when the stud 10 is driven as by a flexible shaft previously referred to, the arms 16 and links 21 will tend to move outwardly because of centrifugal force, to the extent permitted by the surrounding structure. Outward movement of the links, of course, is accompanied by sliding movement of the block 27 toward the block 14. Normally the block 27 lies forwardly of the cutting wheels 20. In using the apparatus of my invention for cleaning the trough-like lower portion or tube of locomotive siphons, the device is inserted longitudinally in the siphon tube after removing the clean-out plug. The stud 10 is then driven while the device is moved longitudinally through the siphon tube. The wheels 20 engage the inner surface of the tube and effectively remove any material deposited thereon. Since the several pairs of arms 16 and links 21 are all tied together, the cutting wheels 20 are all maintained at the same distance from the axis of the stud 10. As a result, since there are always at least three wheels engaging the inner surface of the siphon tube, it is impossible for the device to become bodily displaced and the pairs of pivoted arms and links are therefore prevented from moving outwardly beyond the radius of the siphon tube whether the wheels are in contact with the interior thereof or are opposite the open top thereof. My invention thus constitutes an important improvement over tube cleaners as used heretofore employing three sets of links and cutting wheels since it is possible, with such device, for the links and cutting wheels to move outwardly

when one of them is opposite the open space of the tube to an extent such that it strikes the side of the tube on further rotation.

Experience gained in the use of the device disclosed herein establishes that it is capable of cleaning siphon tubes quickly and efficiently, without any interference resulting from undue spreading of the arms as each arm passes the open top of the siphon tube. The device is simple and may be readily constructed so that it requires no maintenance in service, is always ready for use, and requires no special skill for its manipulation.

Although I have illustrated and described but a preferred embodiment of the invention, it will be recognized that changes in the details of the construction disclosed may be made without departing from the spirit of the invention or the scope of the appended claims.

I claim:

1. A rotary device for cleaning locomotive siphons comprising a stud having means at one end adapted to connect with a drive shaft, a block fixed on said stud adjacent said means and having at least four slots spaced circumferentially of the stud and extending longitudinally thereof, an arm fitting in each of said slots, pivoted to the block and extending forwardly therefrom, a cutting wheel on the free end of each arm journaled to rotate about an axis extending in the same general direction as the axis of rotation of the device, a second block slidably mounted on the distal end of said stud and normally positioned forwardly of the cutting wheels, links pivotally connected to the second block, extending rearwardly therefrom and connected at their rear ends to the arms at intermediate points thereof adjacent to the cutting wheels, the links having legs spaced apart to receive the arms, said legs being spaced apart sufficiently to nest the cutting wheels therebetween when the arms and links are collapsed toward the stud, thereby reducing to a minimum the outside diameter of the device and protecting the cutting wheels when the device is collapsed.
2. A rotary device for cleaning locomotive siphons comprising a stud having means at one end adapted to connect with a drive shaft, a block fixed on said stud adjacent said means and having at least four slots spaced circumferentially of the stud and extending longitudinally thereof, an arm having a flat end fitting in each of said slots, pivoted to said block and extending forwardly therefrom, a cutting wheel on the free end of each arm journaled to rotate about an axis extending in the same general direction as the axis of rotation of the device, the diameter of said cutting wheel exceeding the thickness of said arm, a second block slidably mounted on the distal end of the stud forwardly of the cutting wheels and having the same number of slots circumferentially of the stud as the first-mentioned block, and a wishbone-shaped link for each arm having one end fitting into one of the slots of the slideable block and pivoted thereto, and having a pair of legs extending rearwardly from the slideable block and spaced apart to receive one of the arms therebetween, the ends of the legs being pivoted to the arms intermediate their ends and adjacent the cutting wheels, the intermediate portion of said legs being bowed outwardly to nest said cutting wheels therebetween when the arms and links are collapsed toward the stud, thereby reducing to a minimum the outside di-

ameter of the device when collapsed, the links being also sufficiently bowed outwardly from the stud adjacent the ends thereof which are connected to the sliding block so that the outer surfaces of such bowed portions are farther from the stud than the cutting wheels when the device is collapsed, thereby affording additional protection to the nested cutting wheels.

3. A device as defined by claim 1 characterized by said cutting wheels being journaled on axes

10

sufficiently inclined inwardly from the axes of their supporting arms so that the axes of the cutting wheels are substantially parallel with the inner face of the siphon when the device is expanded and in use and the outer surfaces of the arms are farther from the axis of the stud than the cutting wheels when the device is collapsed.

CLARENCE REYNOLDS.
